UNITED STATES PATENT OFFICE.

CHARLES ROKAHR, OF EL PASO, TEXAS.

ATHLETIC SHOE.

1,286,787.

Specification of Letters Patent.

Patented Dec. 3, 1918.

Application filed October 9, 1917. Serial No. 195,558.

To all whom it may concern:

Be it known that I, CHARLES ROKAHR, a citizen of the United States, residing at El Paso, in the county of El Paso and State of 5 Texas, have invented certain new and useful Improvements in Athletic Shoes, of which the following is a specification.

This invention has relation to boots and shoes, and has for an object to provide an 10 article of this nature constructed on scientific principles, with the anatomy of the human foot in view, so as to provide for greater comfort to the wearer, to properly support the arch, and in general to approach as 15 closely as possible natural conditions in walking.

Another object of the invention is to provide a boot or shoe embodying means in the 20 form of plates located in the sole in positions to support and provide a rest for the astragalus, the scaphoid and metatarsal bones of the foot thereby preventing falling arches and other foot ailments.

A still further object of the invention is 25 to provide means within a boot or shoe to engage the arch from above, and by crowding the foot within the shoe and holding the same, to provide an additional and effective support for the arch.

30 In addition to the foregoing, this invention comprehends improvements in the details of construction and arrangement of parts, to be hereinafter described and particularly pointed out in the appended claims.

35 In the accompanying drawings, in which similar and corresponding parts are designated by the same characters of reference throughout the several views in which they appear:

40 Figure 1 is a view in bottom plan of a shoe with the outer sole removed, illustrating the embodiment therein of my improvements.

Fig. 2 is a view of the shoe in perspective, 45 looking into the interior, and

Fig. 3 is a detail view in section of one of the supporting plates.

The object of my invention is to provide 50 an athletic shoe for exercising, walking, marching or the like, for men, women or children. The results desired are to approach as closely as possible conditions met with in nature. When walking barefooted on soft earth, the earth fills in the underside

of the arch, thereby effectually supporting 55 the same. The conventional type of shoe does not provide for the support of the arch in this manner, the point of contact of the foot with the shoe being too far forward and too far rearward, placing the pressure 60 upon the heel and the ball of the foot. As a result falling of the arch occurs which is caused by the dislocation of the astragalus bone, as well as dislocations of the other tarsal bones. The metatarsal bones are also 65 frequently displaced in a complete falling of the arch.

These conditions are rectified by providing a plate 10 beneath the inner sole of the shoe as indicated in Fig. 1, riveted or otherwise secured therein, and located directly beneath the astragalus bone when the shoe is worn at the point of articulation thereof with the tibia and fibula. The plate is curved slightly longitudinally as shown in 75 Fig. 3. The forward end of the plate terminates at a point directly beneath the forward end of the astragalus bone.

A second plate 11, substantially trapezoidal in configuration is located at a point in 80 advance of the plate 10 so as to be disposed directly beneath the tarsal bones of the foot, and particularly the scaphoid on the inner side of the foot, and the os cuboides on the outer side. One corner of the plate is extended as at 12 to provide for support of the skeleton, and it will be noted that the adjacent edges of the plates 10 and 11 are in 85 spaced relation. This is to provide for flexibility of the sole at a point where it is most desired, and it is there where the major portion of the novelty of my invention resides. The sole of the shoe should be curved longitudinally to conform as closely as possible to the curvature of the underside of the 90 natural foot and to provide what support the semi-rigidity of the leather is capable of. A flap of leather 13 is secured exteriorly to the inner sole before the outer sole is applied so as not to disturb the location of the 95 plates when said outer sole is applied, and to provide additional stiffness.

A pair of tongues 14 are secured interiorly of the shoe, one end of each tongue being secured at a point adjacent the juncture of the 100 sole with the upper, the opposite ends of the tongues being provided with eyelets 15. The tongues are designed to extend across the

arch or instep of the foot at such an angle as to crowd the foot rearwardly toward the heel and therefore tend to create an arch where none exists, or to provide a support 5 for the arch in the natural foot. The tongues are laced and any degree of pressure may be brought to bear on the foot desired to support the arch without causing discomfort.

10 While I have illustrated and described my invention with some degree of particularity, I realize that in practice various alterations therein may be made, and I therefore desire to reserve the right and privilege of changing 15 the form of the details of construction or altering the arrangement of the correlated parts, without departing from the spirit of the invention or the scope of the appended claims.

20 Having thus described my invention, what

I claim as new and desire to secure by Letters Patent is:

A shoe of the character described, having an insole and an outsole, a longitudinally curved plate secured beneath said insole arranged to lie below the astragalus bone of the wearer's foot, a second plate located at a point in advance of said first mentioned plate and disposed below the tarsal bones, and a pair of lacing tongues extending from said insole at an angle arranged to extend over the arch of the foot, whereby the foot may be crowded rearwardly. 25 30

In testimony whereof I affix my signature in the presence of two witnesses.

CHARLES ROKAHR.
